[57] CLAIM

The ornamental design for a slitter, substantially as shown.

DESCRIPTION

FIG. 1 shows our new design for a slitter in perspective view;

FIG. 2 is a side elevation view looking from the right-hand side of the showing of FIG. 1;

FIG. 3 is a bottom view looking upwardly at the slitter shown in FIG. 1;

FIG. 4 is a view looking from the left side of the end of our slitter, as shown in FIG. 1;

FIG. 5 is a top plan view of our slitter;

FIG. 6 is a front end view of our slitter; and,

FIG. 7 is a view of our slitter looking from the unexposed side of FIG. 1;

FIG. 4
